UNITED STATES PATENT OFFICE.

FERDINAND F. BRASCHE, OF EDWARDSVILLE, ILLINOIS, ASSIGNOR OF ONE-THIRD TO CHARLES HOLDING AND ONE-THIRD TO WILLIAM PALECEK, BOTH OF COLLINSVILLE, ILLINOIS.

AUTOMATIC MINE-CAR CAGER.

Application filed November 25, 1921. Serial No. 517,673.

To all whom it may concern:

Be it known that I, FERDINAND F. BRASCHE, a citizen of the United States, residing at Edwardsville, in the county of 5 Madison and State of Illinois, have invented certain new and useful Improvements in Automatic Mine-Car Cagers, of which the following is a specification.

My invention relates to improvements in 10 coal mine car cagers, and has for its object to provide simple and comparatively inexpensive mechanism for automatically caging mine cars and stopping and holding approaching cars so that they may be caused 15 to advance at intervals over a gravity track approaching to the mine cages.

A further object of the invention is the provision of a mine car cager that will be 20 automatic in its operations with the ascending movement of mine cages and thereby prove highly efficient for the purpose intended.

With the above and other objects in view, 25 the invention consists in the novel features of construction, arrangement and combination of parts hereinafter more fully described and finally pointed out in the claims hereto appended.

Referring to the accompanying drawings 30 forming a part of this specification wherein like characters of reference denote similar parts throughout the several views:

Fig. 1, is a plan view of my automatic 35 coal mine car caging device shown as a twin approach equipment to the mine cages within the sump.

Fig. 2, is a view taken on line 2—2 of Fig. 1, in direction of the arrow.

Fig. 3, is a view in end elevation of the 40 tracks adjacent the sump, showing the car controlling mechanism in end elevation.

Fig. 4, is a view taken on line 4—4 of Fig. 1.

Referring to the drawings, the reference 45 character 1 designates the rails of one track indicated A, and 2 the ties therefor, while 1' designates the rails of an adjacent or twin track indicator B, and 2' the ties therefor. 3 indicates the sump. 4 and 5 indicate the mine cages for tracks A and B, respectively. C and D indicate cars shown in dotted lines in Fig. 1, and in full lines in Fig. 2, while E indicates a car shown in dotted lines in Fig. 1. The tracks A and 50 B are inclined from the sump 3.

In carrying out the aim of my invention, I employ a pair of car caging devices designated F and G, each of which are of like construction and arranged between rails of each track, as shown in Fig. 1, with one end 60 thereof extending over into sump 3 in the path of travel of the mine cages 4 and 5 for the purpose of having the mine cages automatically actuate the car caging mechanism or devices F and G, as will be herein- 65 after more fully described.

The car caging device F is shown in Fig. 1 as arranged between the rails of track A while the caging device G is shown in Fig. 1, as arranged between the rails of track B. 70

Each car caging and stopping device F and G consists of a rock shaft 6 positioned between the rails of each track A and B and parallel therewith. The rock shafts 6 are journaled in suitable bearings 7 which 75 are suitably fixed to the ties 2 and 2', as shown in Fig. 1.

Each rock shaft 6 is provided with a pair of car stops designated 8 and 9, and known as first and second stops, respectively. The 80 stops 8 and 9 are positioned at a suitable angle to each other, as will be observed more clearly from Figs. 3 and 4 of the drawings, so that when one stop is in a perpendicular position, its mate will lie at an angle thereto, the reason therefor being apparent hereinafter.

The two rock shafts 6 are connected by means of a suitable connecting rod 10 through the medium of the arms 11, one of 90 which descends from the forward end of each rock shaft 6. The connecting rod 10 is pivotally connected at each end, as at 12 to the descending arms 11 of the rock shafts 6, as clearly shown in Fig. 4. 95

The forward end of each rock shaft 6 is provided with a short shaft 13 journaled in the bearing 14 and hingedly connected to the shafts 6, as at 15. The short shafts 13 are each screw threaded, at the outer end and provided with a securing nut 16. 100

Interposed between each nut 16 and the bearing 14, is a coiled spring 16' which encircles each stub shaft 13 and acts as a shock absorber to reduce the shock when the cars strike the stops 8 and 9 in approaching the mine cages. The pivotal or hinged connection 15 between the short shafts 13 and the rock shafts proper 6, is employed to obviate the necessity of perfect alignment 105 110

between the shafts 6 and 13, as is manifest.

The sump end of each rocker shaft 6 is provided with a downwardly directed arm 17 which is suitably fixed thereto. The free end of each arm 17 is provided with a laterally directed head 18 adapted to be engaged by a suitable shoulder member 19 of mine cages when they are descending for actuating the twin arranged rocker shafts 10 simultaneously and automatically setting the mine cars into motion toward the mine cages.

The operation of the car caging mechanism is as follows:

We will now assume that the mine cage 5 is ascending and approaching the top of the sump 3 with a mine car which has been released from stop 9 of track B, and that the mine cage 4 is descending and at a position in the sump 3 to cause the shoulder 19 of the mine cage 4 to engage the head 18 of rocker arm 17 which arm is now in its uppermost position, as is manifest. At this time, we will assume that there is a mine car C held back by the stop 8 on track A due 25 to the stop being in its perpendicular position which causes the stop member 20 of the car to engage the stop 8, as shown in Fig. 2, and that there is a mine car D upon track B held by the stop 9 owing to its perpendicular position, and, further that there is a mine car E abutting car C on track A but not held back by stop 9 of track A. Now, as the mine cage 4 descends to its lowermost position so that the rails thereof will align 35 with the rails of track A, it moves the rocker arm 16 of track A downwardly in an arcuate path which in turn rocks the rocker shafts 6 of tracks A and B causing the stop 8 and stop 9, respectively to assume an inclined 40 position from their perpendicular positions and the stops 9 and 8 of tracks A and B respectively to move into upright positions, instead of their inclined positions thereby at the same time releasing car C in track A from stop 8 so that it will move onto the mine cage 4 and release car D from stop 9 on track B and allow it to move sumpward to stop 8 of track B ready to be released for loading on mine cage 5 when it has descended. At the same time that the mine cars C 45 and D are moving sumpward, the car E on track A moves sumpward and is stopped by stop 9 which has been moved from its inclined to its upright position during the movement of the rocker arms 6. After the mine cage 4 has been loaded with car C of track A, the cage ascends and cage 5 descends. When the cage 5 comes in contact with the head 18 of arm 17, track B, the stop 50 8 is moved from its upright position to its inclined position thereby permitting car D to roll upon the mine cage 5. At the same time that the stop 8 of track B is moved into its inclined positions, the now upright stop 9 of track A is likewise moved from

its upright position to an inclined position thereby releasing car E so that it may be stopped by stop 8 which is now in an upright position.

It will be observed that when stops 8 and 9 of tracks A and B, respectively, are in their upright positions, that stops 9 and 8 of tracks A and B, respectively, are in their inclined positions, and vice-versa.

From the foregoing description, it is apparent that it is the down going cage that actuates the car stop mechanism which automatically controls the loading of the mine cars upon the mine cages.

The many advantages of the herein described invention will readily suggest themselves to those skilled in the art to which it appertains.

I do not wish to be understood as having limited myself to the details of construction shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such changes, or modifications, as may fairly fall within the scope of the appended claims when fairly construed.

What I claim is:

1. In a mine car cager, a plurality of bearings, a rocker shaft mounted in the bearings between the rails of an inclined track, said rocker shaft comprising two sections hingedly united near one end, a pair of car stops fixed to one section of the rocker shaft and positioned at an angle to each other so that one stop will lie out of car holding position when the other stop lies in car holding position, a crank member fixed to one end of the rocker shaft to be moved downwardly by a descending mine cage to move the car stop in car holding position out of car holding position and to simultaneously move the car stop out of car holding position into car holding position and resilient means mounted upon one end of the rocker shaft and engaging one of the bearings and a nut carried by one end of the rocker shaft to adjust the tension of said spring.

2. In a mine car cager, a pair of rocker shafts mounted between the rails of two inclined tracks, a pair of car stops fixed to each rocker shaft, said stops being so arranged so that one stop will be out of car holding position when the other stop of said rocker shaft is in car holding position, means for connecting the two rocker shafts so they will move in unison, and movable car actuated means operating when moved by a descending mine cage to place the car stops in car holding position out of hold-

ing position and move the car stops out of car holding position into car holding position.

3. In a mine car cager, a pair of rocker shafts mounted between the rails of two inclined tracks, a pair of car stops fixed to each rocker shaft, said stops being so arranged so that one stop will be out of car holding position when the other stop of 10 said rocker shaft is in car holding position, means for connecting the two rocker shafts so they will move in unison, movable car actuated means operating when moved by a descending mine cage to place the car stops

in car holding position out of holding position and move the car stops out of car holding position into car holding position, and means connected to one end of each rocker shaft to act as a shock absorber to reduce the shock imparted to the rocker shaft when 20 a mine car strikes the car holding stops in their approach to the mine cages and to obviate the necessity of perfect alignment of the rocker shafts.

In testimony whereof, I have hereunto 25 signed my name to the specification.

FERDINAND F. BRASCHE.
